HAND-HELD HECTOGRAPHIC CARBON DUPLICATOR

Frederic H. Cordner, 1400 Glengarry Road,
Pasadena, Calif. 91105

Filed July 1, 1974, Ser. No. 484,666

Term of patent 14 years

Int. Cl. D18—02

U.S. Cl. D64—11 B

FIG. 1

FIG. 2

FIG. 1 is a front top perspective view of a hand-held hectographic carbon duplicator showing my new design; and

FIG. 2 is a bottom perspective view thereof.

I claim:

The ornamental design for a hand-held hectographic carbon duplicator, as shown.
